(57) CLAIM

The ornamental design for a gardening glove, as shown and described.

DESCRIPTION

The patent or application file contains at least one drawing executed in color. Copies of this patent or patent application publication with color drawing(s) will be provided by the Office upon request and payment of the necessary fee.

FIG. 1 is a front elevational view of a gardening glove, showing my new design; and,

FIG. 2 is a rear elevational view thereof.

The FUNJOBS trademark forming part of the claimed design is a pending trademark of Melanie Hardie of Australia
